LUBRICANT AND LIQUID COOLANT SUPPLY UNIT

Thomas R. Thomas, New York, N.Y., assignor to Auto
Research Corporation, Boonton, N.J., a corporation
of Delaware

Filed July 7, 1958, Ser. No. 51,683

Term of patent 14 years

(Cl. D65—1)

FIG. 1

FIG. 2

Fig. 1 is a front perspective view of a lubricant and liquid coolant supply unit showing my new design; and Fig. 2 is a side elevational view thereof.

The rear of the article is substantially plain.

I claim:

The ornamental design for a lubricant and liquid coolant supply unit, substantially as shown and described.
